UNITED STATES PATENT OFFICE.

EDGAR HANSTON DULL, OF HANDLEY, WEST VIRGINIA.

ANGLE-BAR.

1,085,553.

Specification of Letters Patent. Patented Jan. 27, 1914.

Application filed June 21, 1913. Serial No. 775,052.

To all whom it may concern:

Be it known that I, EDGAR H. DULL, a citizen of the United States, residing at Handley, in the county of Kanawha and State of West Virginia, have invented new and useful Improvements in Angle-Bars, of which the following is a specification.

The invention relates to an improved angle bar formed to provide an interlocking wedging connection with the bolts used for securing the meeting ends of railroad rails

The main object of the present invention is the provision of an angle bar designed to form one member of a splice or rail joint connection and formed to provide a wedging surface for coöperation with the ends of the bolts so that in properly positioning the bar the bolts will not only be interlocked but wedged in place, maintaining a rigid connection under all conditions.

Figure 1 is a side elevation illustrating the application of the improved angle bar. Fig. 2 is a horizontal section partly in elevation of the same. Fig. 3 is a plan of the securing bolt used with the improved angle bar. Fig. 4 is a vertical section partly in elevation illustrating the use of the improved angle bar.

The improved angle bar comprises a strip or section 1 preferably formed on its upper and lower edges for coöperation with the tread and base flange of the rails. The bar, for each bolt used to secure the rail ends in position, is formed with a longitudinally extending depression 2 opening through the outer surface and having its inner or bottom wall 3 inclined with respect to said outer surface. The side walls of the depression 2 are arranged at right angles to the outer surface of the bar, and the inner or bottom wall of said depression is formed with a longitudinally extending slot 4 of less width than that of the depression, said slot extending through the angle bar as shown. At one end the slot is enlarged or coincides with an opening 5 corresponding approximately to the diameter of the bolts used, the opening 5 being located at the maximum depth of the depression that is at the relatively inner end of the inclined bottom 3 of the depression. The slot 4 beyond the opening 5 is, as previously stated, of less width than the similar dimension of the depression 2 so that the bottom 3 of the de-

pression on each side of the slot forms what 55 may be termed inclined guide ways. The outer surface of the bar above and below the depression 2 is formed with upper and lower ribs 6, the upper rib being preferably somewhat thicker than the lower rib. That 60 is the ribs extend in alinement with the edges of the depression and are formed with a series of openings 6' which are arranged in vertically alined pairs and adapted to receive pins 14 for holding the securing bolts 65 in their adjusted position, as will later appear.

The securing bolts 7 are of the usual headed type, and at the end formed for co-operation with the improved angle bar are 70 cut away on diametrically opposed lines to provide recesses 8 having upper and lower shoulders 9 and 10. If desired the headed ends of the bolts may be provided with projections 12 to coöperate with openings 13 75 in the splice bar on the opposite side of the rail from the improved angle bar, whereby the bolts when positioned with their projections 12 registering in the slots 13 will be properly arranged to locate the recesses 8 80 for the improved angle bar.

In use the bolts in applied position are engaged by the improved angle bar by passing the openings 5 of the respective depressions 2 over the ends of the bolts, so that 85 the recesses 8 register with the walls of the slot within the depression. The angle bar is then forced longitudinally causing the shoulders or guide ways 3 to engage the outer shoulders 10 of the recesses 8 of the 90 bolts, and by reason of the inclined or wedged formation of said guide ways draw the bolts into a clamping locked position. The longitudinal movement of the angle bar is continued until the bolts are securely 95 locked whereupon auxiliary pins 14 are passed longitudinally through the particular openings 6 between the bolt in its locked position and the entrance openings 5 of the bolt. The reverse movement of the angle 100 bar thus prevented it is to be understood that the opening immediately adjacent and in rear of the bolt 7 is used to receive the holding auxiliary pin 14.

In the use of the improved angle bar, a 105 uniform tight joint is provided in which the parts are held against possibility of separation, the dispensing with the nuts gained

through the improved construction, removing the prime cause of the loose joint connections.

What is claimed is:—

- 5 In a rail joint the combination with a shouldered securing bolt of an angle bar formed with inclined ways to coöperate with the shoulders of the bolts, said angle bar being formed with a depression opening 10 through the outer surface and having an inclined inner or bottom wall, said angle bar being formed with a slot opening through the inner side of the bar and the inclined bottom of the depression, said slot being of

less width than the similar dimension of 15 the inclined bottom wall of the depression, the terminal of the slot being enlarged to form an entrance opening, the opposing walls of the bar beyond the depression being provided with ribs formed with registering 20 openings to receive an auxiliary pin.

In testimony whereof I affix my signature in presence of two witnesses.

EDGAR HANSTON DULL.
